CLAIM

The ornamental design for a motorcycle air cleaner cover, as shown and described.

DESCRIPTION

FIG. 1 is a side elevational view of a motorcycle showing my new motorcycle air cleaner cover design;

FIG. 2 is an enlarged perspective view showing my new motorcycle air cleaner cover mounted on an air cleaner;

FIG. 3 is an enlarged perspective view of my new motorcycle air cleaner cover;

FIG. 4 is an enlarged front elevational view thereof;

FIG. 5 is an enlarged rear elevational view thereof;

FIG. 6 is an enlarged top plan view thereof, it being understood that the bottom plan view is a mirror image thereof; and,

FIG. 7 is an enlarged side elevational view thereof.

The portions shown in broken lines in FIGS. 1 through 4 are for illustration only and form no part of the claimed design.
